HORACE H. BURDETT, OF HOPEDALE, MASSACHUSETTS, ASSIGNOR TO DRAPER CORPORATION, OF HOPEDALE, MASSACHUSETTS, A CORPORATION OF MAINE

SELVAGE-TRIMMING MECHANISM

Application filed May 9, 1928. Serial No. 276,419.

This invention relates to a mechanism for trimming off close to the selvage the filling ends left projecting therefrom during the weaving operation. Such ends occur particularly as a result of the operation of the automatic filling replenishing loom wherein each time the filling is changed or replenished, both the discharged filling carrier and the fresh filling carrier leave ends projecting at the selvage which must be removed. The mechanism commonly employed for trimming off these ends is usually combined with the temple and located beyond the end of the cloth engaging roll of the temple. Consequently these ends are not severed close to the selvage and, especially in the case of the finer grades of cloth, have to be further removed by subsequent operations.

It is the object of the present invention to provide filling cutting mechanism having its field of action located in the rear of the temple roll and between the planes of the ends of the temple roll so that with the cloth held by the temple roll and with the selvage of the cloth thus passing around the temple roll and between the ends of the temple roll, the cutting mechanism may be located close up to the selvage and thus enable the filling ends extending from the selvage to be severed close to the selvage.

It is the object of the invention further to provide a selvage trimming mechanism which shall have its field of action close to the selvage.

It is the object of the invention further to provide such a mechanism which may be supported by the usual temple.

It is the object of the invention further to provide such a mechanism so arranged that it may be laterally positioned on and with respect to its support, such, for example, as the temple, to maintain its field of action close to the selvage.

It is the object of the invention further to provide such a mechanism in which the cutting elements shall be yieldingly maintained against the selvage so as to insure severing the ends close to the selvage under all conditions.

These and other objects and features of

the invention will appear more fully from the accompanying description and drawings and will be particularly pointed out in the claims.

As the invention is applicable to all types of looms and is concerned only with the severing of the filling ends at the selvage, it is only necessary here to illustrate and describe a preferred form of the invention and those parts immediately associated therewith. In its broader aspect the mechanism may be carried by any suitable support, but in the preferred form the shank of an ordinary temple is utilized as such a support. So also the cutting mechanism may be periodically operated by any suitable means, but is here illustrated as conveniently operated by the movement of the lay of the loom, as in the case of the cutting mechanism usually embodied in a thread cutting temple.

In the drawings:

Fig. 1 is a top plan view of an ordinary type of temple with a preferred form of the invention supported thereby, all shown in position in relation to a piece of cloth being woven in a loom.

Fig. 2 is a side elevation of the construction shown in Fig. 1 with the lay of a loom indicated in dotted lines.

Fig. 3 is a detail chiefly in transverse cross section on the line 3-3 of Fig. 2.

Fig. 4 is a perspective view of a portion of the construction looking from the rear and showing a filling end in position to be severed.

While, as already noted, a mechanism of this invention may be mounted on any suitable support, it is convenient to utilize the shank of an ordinary temple for that purpose and the invention in some of its features involves the combination with a temple. Such a temple is illustrated having the usual stand 1 mounted on a bracket 2 connected to and supported by some portion of the loom frame, such as the breast beam. This stand extends rearwardly adjacent the edge of the cloth being woven. The shank 3 of the temple is mounted to slide in the stand being pressed rearwardly by a spring, not shown, in the stand, and moved forward slightly upon the beat-up by the lay 4 striking against

a heel 5 depending from the stand. At its rearward end the shank is formed into or supports the transversely extending head 6 in which is journalled the usual temple roll 7, here shown of the pin type, which acts to maintain the width of the cloth as it is woven. The temple head embraces the cloth directly forward of the fell 8 and straddles the selvage 9 of the cloth.

10 In the form of the invention here illustrated, the shank 3 of the temple which forms the support has mounted therein a laterally extending rod 10 which extends just forward of the temple head 6 above the plane of the cloth. Forward of this rod the shank 3 is provided with a laterally extending hub 11 forming a bearing and in this bearing a shaft 12 is mounted both to slide and rotate.

15 The cutting mechanism comprises a pair of cooperating cutter blades which operate in a plane substantially normal to the path of the cloth and which stand substantially parallel to the selvage forward of the fell. In the preferred construction, one of these blades, herein referred to as the main blade, has no movement during the cutting operation, while the other of these blades, herein referred to as the movable blade, is moved or rocked relatively to the main blade to effect the cutting operation.

20 The main cutter blade is shown as a metal plate 13 recessed at its bottom edge to fit over the temple head and present its effective or cutting edge just forward of the fell and just rearward of the temple head, while its body portion is supported by the rod 10 and shaft 12. As illustrated, this plate 13 has rigidly secured thereto and projecting laterally therefrom a hub 14 fitting the rod 10. Forward of this hub the plate 13 is apertured to fit over a cap 15 mounted on the end of the shaft 12. At its rear end the plate 13 is formed into a narrow vertical finger 16 adapted to rest against the edge 9 of the cloth and presents a notch 17 in the plane of the cloth to receive the filling end 18 as the cloth advances in the weaving operation. The cutting edge of the blade 13 is presented at the edge of this notch.

25 The movable cutter blade 19 is shown as of generally hook shape. At its rear end it presents a bevelled cutting edge 20 adapted to slide down in close contact with the outer surface of the finger 16 and as it passes across the notch 17 to sever the filling end close to the edge 9 of the cloth. This movable cutter member 19 at its forward end is secured to the shaft 12. For this purpose it is shown as fitting over the shaft 12 and clamped between the shoulder 21 on the shaft and the cap 15, which is threaded to the end of the shaft. A pin or key 22 also locks it to the shaft 12 so as to insure its partaking of the rotary movement of the shaft.

30 65 Suitable means are provided for pressing

the cutter blades 13 and 19 together to insure the cutting action. In the construction illustrated, the movable blade 19 has secured thereto and projecting laterally therefrom a stud 23 passing through an arcuate slot 24 in the main blade 13. This stud has mounted thereon a helical spring 25 held in place between washers 26 and 27, the outer of which abuts against a cotter pin 28 in the end of the stud so that the spring acts to press the two blades together.

35 The blades are opened to receive the filling end, in the case illustrated, by rocking the movable cutter blade 19 upward and for that purpose a spring 29 is shown coiled at its center about the sleeve 15 and hooked at one end over the hub 14 and at the other end over the stud 23. At the latter end the spring 29 is shown as located between the washer 27 and another washer 30. Thus this spring 35 normally acts to elevate the movable cutter blade 19. The cutting operation of the blades which should occur periodically is conveniently secured from the lay at each beat-up and for that purpose the shaft 12 has adjustably secured thereto, as by the set screw 31, a depending arm 32 extending radially from the shaft into the path of the lay 4. Thus at each beat-up the shaft 12 is rocked, causing the movable cutter blade 19 to rock 40 downward and effect the cutting operation and then as the lay retracts, the spring 29 rocks the movable cutter member 19 and therewith the shaft 12 and arm 32 in the opposite direction.

45 An important feature, however, is that this entire cutting mechanism comprising the pair of cooperating cutter blades such as 13 and 19 are positionable, and in the preferred form of the invention position themselves automatically, to maintain the blades close up against the selvage forward of the fell so as to sever the ends close to the selvage. The cooperating blades are arranged to have a joint movement relative to the support toward and from the selvage. It will be seen from the illustrative construction already described that the main blade 13 with its hub 14 may be moved laterally on the rod 10, carrying with it the movable cutter blade 19 and the shaft 12, which slides in its bearing in the hub 11. Thus the entire cutting mechanism is readily positioned laterally to bring the finger 16 into contact with the selvage just forward of the fell. This position may be determined manually when desired and the parts will then be locked in place, as, for example, by setting up the set screw 33 to lock the hub 14 to the rod 10. Preferably, however, this positioning of the blades in the desired relation to the selvage is automatically secured by means which act yieldingly to press the finger 16 against the selvage. As a preferred means of securing this result, the inner end of the rod 10 is surrounded by a

light helical spring 34. This spring at its outer end is secured to the hub 14 and at its inner end abuts the end of the rod 10. Thus the spring has a constant tendency to move the cutter blades up against and maintain them against the selvage of the cloth. This spring should be made very light and it is assisted in its function by the shock and jar of the loom. It may be desired to limit the inward movement of the cutter blades toward the selvage while allowing the blades to move yieldingly outward as the path of the selvage through the temple changes slightly. This result is readily secured by adjusting the arm 32 longitudinally on the shaft 12 so that it will contact with the hub 11 when the blades are in the desired position.

The operation of the mechanism illustrated will be apparent. After the filling is beaten in, if an end is left extending from the selvage it will be carried into the notch 17 and on the next beat-up thereafter will be severed by the blade 19 close to the selvage. If the end is held by such a mechanism as the usual filling clamping and parting mechanism on a shuttle feeler, it will stand as shown in Fig. 4 and a notch 35 is shown in the temple head to assist in positioning such a long end.

Another important feature of this invention is that with any type of temple having a roll journaled on an axis substantially parallel with the fell of the cloth being woven, the field of action of the cutting mechanism is located in the rear of the roll and between the planes of the ends of the roll. The cloth held by the temple roll uniformly has its selvage passing around the temple roll and between the ends of the roll. Heretofore the cutting mechanism operated beyond the end of the roll and so could not be brought up close to the selvage. With this invention the field of action of the cutting mechanism, since it lies at the rear of the temple roll and between the planes of the ends of the temple roll, is brought up close to the selvage, thus enabling the filling ends to be cut close to the selvage. While but one form of temple roll is illustrated, it is obvious that the invention is independent of the particular character of roll, or its surface, or whether it is made in one or more sections provided that its axis is generally parallel with the fell. Nor is the invention to be limited to any particular form of cutting mechanism so far as the broader aspects of the invention are concerned.

In the form of the invention shown, no other mechanism is necessary for severing the filling ends or trimming the selvage and the usual cutting mechanism employed in the temple may be dispensed with. The field of action of the cutting blades may be positioned through a wide range of lateral move-

ment and thus under all conditions be located close to the selvage.

Having thus described the invention, what is claimed as new, and desired to be secured by Letters Patent, is:

1. A thread cutting loom temple comprising a shank supported from the loom frame, a head on the shank having a temple roll journaled therein, a pair of cooperating cutter blades extending in the rear of and adjacent to the temple head in a vertical plane and mounted on the temple forward of the head for joint bodily lateral movement with respect to the head and means for effecting the cutting operation of the blades to sever close to the selvage the filling ends extending therefrom. 70

2. A thread cutting loom temple comprising the construction defined in claim 1, together with adjustable means for limiting the bodily lateral movement of the blades toward the selvage. 85

3. A thread cutting loom temple comprising the construction defined in claim 1, together with means for locking the blades in desired position relatively to the selvage. 90

4. A thread cutting loom temple comprising the construction defined in claim 1, together with means acting yieldingly to move the blades laterally toward the selvage. 95

5. A thread cutting loom temple comprising a shank supported from the loom frame, a head on the shank having a temple roll journaled therein, a laterally extending rod mounted in the shank, a bearing in the shank parallel with the rod, a shaft in said bearing, a main cutter blade mounted to slide on the rod and connected to the shaft to slide therewith and extending at the rear of and adjacent to the temple head, a movable cutter blade mounted to move laterally with the main cutter blade and held yieldingly thereagainst and connected to the shaft to slide and rock therewith and means for periodically rocking the shaft to effect the cutting cooperation of the blades. 100

6. A thread cutting loom temple comprising a shank supported from the loom frame, a head on the shank having a temple roll journaled therein, a laterally extending rod mounted in the shank, a bearing in the shank parallel with the rod, a shaft in said bearing, a main cutter blade mounted to slide on the rod and connected to the shaft to slide therewith and extending at the rear of and adjacent to the temple head, a movable cutter blade mounted to move laterally with the main cutter blade and held yieldingly thereagainst and connected to the shaft to slide and rock therewith and an arm extending radially from the shaft into the path of the lay and acting when struck on the beat-up to rock the shaft and effect the cutting action of the blades. 115

7. In a loom, a temple having a temple 120

130

roll journaled therein on an axis parallel with the fell of the cloth being woven and filling cutting mechanism having its field of action located in the rear of the first roll surface engaged by the cloth in its passage through the temple and between the planes of the ends of the said roll surface whereby the cutting mechanism may sever close to the selvage filling ends extending from the cloth held by the temple roll with the selvage passing around the roll and between the ends of the roll.

8. In a loom, a temple having a temple roll journaled therein on an axis parallel with the fell of the cloth being woven and filling cutting mechanism having its field of action located in the rear of the roll and between the planes of the ends of the roll, the said cutting mechanism being bodily movable longitudinally of the roll to enable it to be adjusted close to the selvage of the cloth held by the temple roll with the selvage passing around the roll and between the ends of the roll whereby the cutting mechanism will act to sever close to the selvage filling ends extending therefrom.

9. In a loom, the construction defined in claim 8, together with means acting yieldingly to maintain the cutting mechanism against the selvage.

10. In a loom, the construction defined in claim 8, together with means for locking the cutting mechanism in adjusted position.

11. A thread cutting loom temple comprising a head having a temple roll journaled therein, means for supporting the temple head from the loom frame with the axis of the temple roll parallel with the fell of the cloth being woven, a pair of cooperating cutter blades extending in the rear of the first roll surface engaged by the cloth in its passage through the temple and between the planes of the ends of the said roll surface and mounted on the temple, whereby the field of action of said blades may be located close to the selvage of the cloth held by the temple roll with the selvage passing around the roll and between the ends of the roll and means for effecting the cutting operation of the blades to sever close to the selvage filling ends extending therefrom.

12. A thread cutting loom temple comprising the construction defined in claim 11, in which the said cutter blades are mounted on the temple for joint bodily lateral movement longitudinally of the roll to enable the said blades to be adjusted with relation to the selvage, together with means for locking the blades in desired position relatively to the selvage.

13. Selvage trimming mechanism for looms comprising a support mounted on the loom frame and extending in the vicinity of the selvage forward of the fell, a pair of cooperating cutter blades operating in a plane sub-

stantially normal to the path of the cloth and substantially parallel to the selvage forward of the fell and mounted on the support for joint bodily movement with respect to the support toward and from the selvage, means acting yieldingly to move the blades toward the selvage, a stop adjustable in the direction of such movement for limiting the movement of the blades toward the selvage, and means for effecting the cutting operation of the blades whereby the blades may be positioned to sever close to the selvage filling ends extending therefrom.

14. Selvage trimming mechanism for looms comprising a support mounted on the loom frame and extending in the vicinity of the selvage forward of the fell, a pair of cooperating cutter blades operating in a plane substantially normal to the path of the cloth and substantially parallel to the selvage forward of the fell and mounted on the support for joint bodily movement with respect to the support toward and from the selvage, whereby the blades may be positioned to sever close to the selvage filling ends extending therefrom, means for locking the blades when positioned in desired relation to the selvage against further joint bodily movement, and means for effecting the cutting operation of the blades.

15. A thread cutting loom temple comprising a head having a temple roll journaled therein, means for supporting the temple head from the loom frame with the axis of the temple roll parallel with the fell of the cloth being woven, a pair of cooperating cutter blades extending in the rear of the roll and between the planes of the ends of the roll and mounted on the temple for joint bodily lateral movement longitudinally of the roll to enable the said blades to be adjusted with relation to the selvage, whereby the field of action of said blades may be located close to the selvage of the cloth held by the temple roll with the selvage passing around the roll and between the ends of the roll, and means for effecting the cutting operation of the blades to sever close to the selvage filling ends extending therefrom.

16. A thread cutting loom temple comprising a head having a temple roll journaled therein, means for supporting the temple head from the loom frame with the axis of the temple roll parallel with the fell of the cloth being woven, a pair of cooperating cutter blades extending in the rear of the roll and between the planes of the ends of the roll and mounted on the temple for joint bodily lateral movement longitudinally of the roll to enable the said blades to be adjusted with relation to the selvage, means acting yieldingly to move the blades toward the selvage, whereby the field of action of said blades may be located close to the selvage of the cloth held by the temple roll with the selvage passing

around the roll and between the ends of the roll, and means for effecting the cutting operation of the blades to sever close to the selvage filling ends extending therefrom.

5 In testimony whereof, I have signed my name to this specification.

HORACE H. BURDETT.
